UNITED STATES PATENT OFFICE

RALPH K. REYNOLDS, OF DANBURY, CONNECTICUT, ASSIGNOR TO MALLORY HAT COMPANY, OF DANBURY, CONNECTICUT, A CORPORATION OF CONNECTICUT

ART OF FITTING SWEATBANDS FOR HATS AND APPARATUS THEREFOR

Application filed January 12, 1927. Serial No. 160,589.

This invention relates to hat manufacture and more particularly to an art or method of fitting sweat-bands into hats, and apparatus therefor.

5 One of the objects of the invention is to provide a method of fitting sweat-bands into hats which is practical and highly efficient. Another object is to provide a method of the above nature whereby the accuracy and uniformity of the head sizes of the finished hats are greatly improved. Another object is to provide a method of the above nature which may be conveniently carried on and which results in a saving of labor and time over the methods employed heretofore. Another object is to provide practical and efficient apparatus for carrying out the above method or process. Another object is to provide such apparatus which is simple and convenient to operate. Other objects will be in part obvious or in part pointed out hereinafter.

The invention accordingly consists in the features of construction, combinations of elements, arrangements of parts and in the several steps and relation and order of each of the same to one or more of the others all as will be illustratively described herein, and the scope of the application of which will be indicated in the following claims.

20 In the accompanying drawings in which is shown one of the various possible embodiments of the mechanical features of this invention,

Figure 1 shows a sweat-band prior to its being fitted to a hat;

Figure 2 shows the sweat-band cut or trimmed to size;

Figure 3 is a side elevation of a finished hat partly broken away to show the sweat-band therein;

Figure 4 shows in dotted lines the hat in inverted position and the sweat-band in full lines;

Figure 5 is a plan view of an apparatus for cutting the sweat-bands to size;

Figure 6 is a front elevation of the apparatus;

Figure 7 is a section taken along the line 7-7 of Figure 6;

Figure 8 is a section taken along the line 8-8 of Figure 6;

Figure 9 is a section taken along the line 9-9 of Figure 6, and

Figure 10 is a fragmentary view of parts 55 of the apparatus shown in Figure 6.

Similar reference characters refer to similar parts throughout the several views of the drawings.

As conducive to a clearer understanding of certain features of this invention, it may be here noted that in the manufacture of hats, for example, felt hats, the hats are made in various head sizes which are indicated by well known size marks. Ordinarily the sizes 60 will run from about size 6½ or a little smaller up to size 8 or a little larger, the intermediate sizes being graduated in one-eighths; for example, in a given style of hat the manufacturer must make sizes 6½, 6¾, 6¾, 6¾, 7 and so on up to about size 8 in order to be reasonably certain of having a size which will fit the head of any wearer.

It is endeavored to have all hats which are marked for a given size, for example, size 7½, actually of the same head size when the hats are completed in order that a man who knows that he wears a size 7½ hat, for example, may select any hat marked 7½ and know that it will fit. This uniformity of sizes is 80 greatly to be desired, as will be readily understood, but with the methods of hat manufacture heretofore employed it has not been successfully achieved, the finished hats which are supposed all to be of the same size actually 85 varying very substantially in their head measurements.

The hat bodies vary in size after they have been blocked and brought to shape and are ready to be trimmed, or to have the bands or 90 bindings and sweat-bands added thereto to complete the hat. These variations may be due to variations in the blocks upon which the hats are brought to shape or they may be caused by other circumstances in the progress of the hat body through its manufacturing process. The sweat-band of the hat is the part of the hat which rests against the head of the wearer, and the proportions of the sweat-bands are thus determinative of the 95 100

head sizes of the finished hat. In the methods commonly employed, when the sweat-band is fitted into the hat it is simply cut to such length that it will fit the hat being 5 trimmed and is then fastened in place in that hat. The result is that variations in the sizes of the hat bodies which are supposed to be of a given size are not discovered and the inaccuracies are not corrected but in many 10 cases are aggravated in the completed hat. It is one of the dominant aims of this invention to provide a method of fitting sweat-bands into hats which overcomes these difficulties and not only results in a great improvement in the accuracy of the head sizes 15 of the finished hats but which is more expeditious than the methods heretofore employed.

Referring now to the drawings, there is 20 shown in Figure 1 a sweat-band 10. These sweat-bands are ordinarily of leather and they are made up in large quantities and generally obtained by the hat manufacturers in quantities and in substantially the shape 25 shown in Figure 1. They are made in the curved shape shown in order to fit the "scope" of the hats into which they are to be fitted. By the "scope" of the hat is meant the curved shape of the hat at the band whereby the band 30 is higher at the sides of the hat than it is at the ends, as is brought out in Figure 3. The sweat-bands 10, as they are made up and as shown in Figure 1, are rough at the ends and of a length greater than required in the hat. 35 In the methods heretofore employed, the operator selects a hat band such as 10, of too great length, and inserts it into the hat where the sweat-band is intended to be placed, with the rough ends over-lapping. Thereupon, 40 the operator makes a suitable mark upon the band at the points where it requires to be cut in order to reduce the sweat-band to a length adapted to just fit into the hat with the ends thereof in abutting relation. Ordinarily the 45 abutting ends are placed at the rear of the hat, as indicated at 11 in Figure 4. The operator then cuts the band in accordance with the mark made thereon and then fastens the ends in abutting relation by means of a 50 sticker applied to the rear side of the sweat-band, and perhaps a few stitches. The sweat-band is then sewed into the hat to which it has thus been fitted, for example, by means of stitches such as shown at 12 in Figure 3. 55 In addition to marking and cutting the sweat-band so that it will fit into the hat the operator attempts to make the cuts so that when the ends are abutted the sweat-band has somewhat of a cone shape or funnel shape as 60 may be seen in Figures 3 and 4, the edge 13 of the band being shorter than the edge 14. Thus, it will be seen that no attempt is made to discover or correct inaccuracies in the size 65 of the hat. If the hat body is smaller than is desired for the head size of the finished hat,

the head size is made still smaller by the insertion of the band and, if the hat body is too large, it is still too large after the sweat-band is sewed in.

In accordance with the present invention, 70 before the rough sweat-band 10 is introduced to the hat, its ends are cut to give such a length and shape that when the ends thereof are placed in abutting relation the sweat-band itself gives a predetermined head size 75 and, in addition, the desired cone shape or funnel shape. For example, if a lot of hats which are to be size 7 are ready to have sweat-bands applied thereto, a sufficient number 80 of sweat-bands are cut to supply these hats and each one is cut to a length which will give exactly the head size 7. The ends of the sweat-bands are then secured together in abutting relation and then, for the first time, 85 the sweat-bands are introduced into the hats. If the hat is too small to give a finished head size of 7, the sweat-band will not go into the hat and this hat is rejected and either re-blocked or used for a smaller size. If the hat body is slightly too large, the sweat-band will 90 correct the size and the finished hat with the sweat-band therein will be exactly the size 7 which it was intended to be.

It will be seen that the operator who sews 95 the sweat-band into the hat is required to do no fitting whatever but simply places the two ends of the prepared sweat-band together and pastes a sticker on the unfinished side of the two abutting ends. The sweat-band acts 100 as a gage, indicating at once whether or not the hat body is of the size that it should be. Inaccuracies and non-uniformity in the sizes 105 of the finished hats are effectively avoided. In addition, a very substantial saving in time and labor is effected and danger of spoiling sweat-bands by careless cutting on the part 110 of the operator is avoided. The ends of the bands may all be cut at a uniform angle so that the desired cone shape or funnel shape 115 will be present and uniform in the sweat-band of each finished hat.

Referring now to Figure 5, there is shown 120 a sweat-band 10 being cut to shape and size, as has been described above. Due to the curved shape of the sweat-band to fit the 125 scope of the hats, the sweat-band has a so-called center or center line which is indicated at 10a in Figure 1 and in Figure 5. The rough sweat-band is doubled upon itself along the center line 10a and the loop is placed about a horizontal support 15 which preferably takes the form of a round rod. This rod is secured to and projects outwardly 130 from a bracket 16 which is in turn secured to the left-hand end of a horizontally slidable member 17. This member 17 is mounted upon and slidable upon a table or plate 18, as will be described in detail presently, and the table 18 rests upon a base 19. At the 135 right-hand end of the base 19 is a straight

edge 20 cooperating with which is a knife 21. The knife 21 is pivoted to the base 19 at 22 and at its free end is provided with a handle 23 by means of which it is operated.

5 The folded sweat-band 10 having been slipped over the supporting rod 15, the two folded portions thereof are registered, one above the other, and the edges are alined by sliding the edges 14 against a plate 24 which 10 projects upwardly from the surface of the table 18. The position of the leather sweat-band upon the table 18 is thus determined by the supporting rod 15 and the guiding plate 24. The ends of the sweat-band project over 15 the straight edge 20 and beneath the knife 21 and, by now bringing the knife down, the two ends of the sweat-band are cut off along a line determined by the straight edge 20.

The distance between the supporting rod 20 15 and the edge 20 determines the length to which the sweat-band is cut. The table 18 is preferably pivotally mounted upon the support 19, by a pivot post 25, so that the angular position of the table with respect to 25 the edge 20 may be adjusted. A locking screw 26, passing through an arcuate slot in the table, is provided for locking the table in the position to which it is adjusted about the pivot 25. By this adjustment about the pin 20 25 there is determined the angle at which the ends of the sweat-band are cut when the knife is operated. This angle is adjusted to give the desired cone shape or funnel shape 30 to the sweat-band when the ends thereof are placed in abutting relation.

The member 17 carrying the supporting rod 15 is adjustable in position lengthwise of the table 18 and hence toward and away from the straight edge 20. The right-hand portion of the member 17 is split into two spaced parts 17a and 17b between which is a guide 27 the edges of which overhang the parts 17a and 17b and which guides the member 17 in its sliding movement. Upon the surface of the table 18 adjacent to the part 17a is a raised portion 28 which is graduated lengthwise by markings indicating head sizes. Secured to the slidable part 17a is a pointer 29 overhanging the surface of the part 28 and adapted to coact with the markings or graduations thereon.

The marks upon the portion 28 are so positioned thereon that, when the pointer indicates a given head size, the supporting rod 15 is positioned at such distance from the straight edge 20 that, when the knife 21 is operated, the leather sweat-band is cut to precisely the required length to give that head size. For example, if it be desired to cut a sweat-band for a size 7 the slidable member 17 with its parts 17a and 17b is moved along the table 18 until the pointer 29 registers with the mark 7 upon the scale 28; the knife is then operated to cut off the ends of the sweat-band and the resulting length of the sweat-band is

such that when the ends thereof are placed in abutting relation the sweat-band gives the head size 7.

Mounted upon the surface of the table 18, to the left of the portion 28, is a bracket 30 70 having an upstanding lug 31 in which is supported a pivot pin 32. As best shown in Figure 6, there is pivoted upon the pin 32 a bell crank lever the long arm 33 of which forms a handle and the short arm 34 of which 75 has pivoted thereto, at its lower end 35, a pawl 36. In the upper surface of the part 17b are ratchet teeth 17c with which this pawl 36 coacts. The end of the pawl rests by gravity against the ratchet teeth. A spring 80 37 coiled about the pin 32 bears against the arm 33 of the bell crank lever and normally holds the lever in the position shown in the drawings, with the arm 34 thereof against a stop pin 38 which is mounted upon the lug 85 31. By depressing the handle or arm 33 of the bell crank the member 17 and the supporting arm 15 are moved to the right through the action of the pawl 36 upon the ratchet teeth 17c. 90

The part 17a of the member 17 is provided in its upper surface with a series of indexing notches 17d which are evenly spaced apart a distance equal to the distance between adjacent size marks on the part 28. Cooperating with the indexing notches 17d is an index finger 39 (Figure 6) which is at the right-hand end of a bar 40. The bar 40 at its left-hand end 41 is pivoted upon a bracket 42 projecting from the surface of the table 100 18. The index finger 39, cooperating with the notches 17d, is for the purpose of positioning the support 17 so that the pointer 29 will register exactly with the respective size marks upon the part 28. When the index finger 39 is in engagement with a notch 17d the part 17 and the supporting rod 15 are locked in a predetermined position and in such position that the pointer 29 registers 105 with one of the size marks. 110

For lifting the index finger 39 out of the notches, there is provided a lever pivoted upon the pin 32 having a handle portion 43 and a portion 43a which is connected by a link 44 with the bar 40 adjacent to the index finger 39. A spring 45, which is coiled about the pin 32, urges the index finger downwardly and normally holds the parts in the position shown in the drawings. By depressing the handle 43 the index finger 39 is raised from the part 17a thereby releasing the member 17 for movement along the table toward or away from the straight edge 20. 115

In the use of this apparatus, the operator starts by first cutting the sweat-bands which are to be given the largest head size of the lot which he has on hand to be cut. If this largest size is size $7\frac{1}{2}$, for example, the operator positions the slide 17 so that the pointer 29 indicates the size mark $7\frac{1}{2}$. If it is 120 125 130

necessary to move the slide 17 to the left, the pawl 36 may be lifted out of engagement with the ratchet teeth 17c by means of a pin 36a (Figure 6). When the slide has been moved 5 so that the pointer 29 indicates the size mark 7½, the index finger 39 rests in one of the index notches 17d and the slide is locked against movement in either direction. The operator now places over the supporting rod 10 15, as has been explained above, a sweat-band which is to be cut to the head size 7½, and he then brings down the knife 21; without changing the adjustment of the apparatus the operation is repeated upon all of the 15 sweat-bands which are to be given the head size 7½.

The operator now adjusts the apparatus to 20 cut the sweat-bands which are to be given the size 7¾. In order to accomplish this adjustment, the handle 43 is depressed to lift the index finger 39 and, with the same movement, the handle 33 is depressed to actuate the pawl 36 and move the slide 17 to the right. As the handle 33 is depressed the handle 43 is released and thereupon, as soon as the slide 17 25 has been moved a sufficient distance, the index finger 39 drops into the next notch 17d and locks the slide against further movement and with the pointer 29 indicating the size 7¾. The operator then cuts all of the sweat-bands 30 which are to have the head size 7¾ and thereupon goes to the next smaller size, 7¼, and so on down to the smallest size. It will be seen 35 that the operation is extremely simple and may be carried on rapidly with dependably accurate results. Each sweat-band is cut to exactly a predetermined size which is to be the head size of the hat into which that sweat-band is to be fitted.

40 After the sweat-bands have been cut to size as above described, they are passed on to the operator who is to fasten the ends thereof in abutting relation and sew them into the hats. It will be seen that the head sizes of the 45 finished hats will be accurate and uniform throughout. If a hat which when finished is to have a given head size will not properly take a sweat-band which has been cut for that size, the hat is rejected and inaccuracies are thereby at once detected and corrected. These 50 advantages are accomplished with an actual saving in time and labor over the methods heretofore commonly employed.

55 As many possible embodiments may be made of the mechanical features of the above invention, and as the art herein described might be varied in various parts all without departing from the scope of the invention, it is to be understood that all matter hereinabove set forth or shown in the accompanying drawings is to be interpreted as illustrative and not in a limiting sense.

I claim as my invention:

1. In apparatus of the class described, in 65 combination, a cutting tool, means for sup-

porting a sweat-band with its end portion in operative relation to said tool, means for adjusting said support with respect to said tool to adjust angularly the position of said sweat-band with respect to said tool, means for moving said support bodily toward and away from said tool, and means for operating said tool to cut off the end of said sweat-band. 70

2. In apparatus of the class described, in combination, a knife, a straight edge adapted to cooperate with said knife, means adapted to support a sweat-band with an end portion thereof overhanging said straight edge, means for adjusting said support angularly to adjust the angular relation between said straight edge and said portion of the sweat-band thereover, means for moving said support bodily toward and away from said straight edge, and indexing means for controlling said last movement, said indexing means being so graduated that each portion of said support determined thereby gives when said knife is operated a length of sweat-band adapted for a predetermined head size. 75 80 85 90

3. In apparatus of the class described, in combination, a cutting tool, a support for holding a folded sweat-band relatively immovable thereon with the juxtaposed ends of said band in operative relation to said tool, said support being movable in a direction lengthwise of said folded band toward and away from said tool, means for operating said tool to cut off the end portions of said sweat-band, indexing means for positioning said support with respect to said tool, said indexing means being graduated in head sizes for hats, and means for moving said support adapted when actuated to move said support with respect to said tool through a distance 95 100 105 equal to the distance between two adjacent graduations of said indexing means.

4. In apparatus of the class described, in combination, a cutting tool, a support for a folded sweat-band movable in a direction to move said folded sweat-band lengthwise toward and away from said tool and adapted to position said folded sweat-band with its end portions in operative relation to said tool, means for operating said tool to cut off the end portions of said sweat-band, means for positioning said support in a plurality of different positions with respect to said tool, each of which positions results when said tool is operated in the cutting of said sweat-band to a 110 length adapted to give a predetermined head size, and means movable relatively to said support for stepping said support progressively from one of said positions to another thereof. 115 120 125

5. In apparatus of the class described, in combination, a cutting tool, a slide movable toward and away from said tool, a support for a folded sweat-band comprising an arm projecting outwardly from said slide adapted 130

- to enter the loop of said folded sweat-band and adapted to position said sweat-band with the end portions thereof in operative relation to said tool, indexing means graduated in head sizes adapted to indicate the position of said slide with respect to said tool and means movable relatively to said slide and operable for imparting a step-by-step movement of said support toward said tool.
6. In apparatus of the class described, in combination, a cutting tool, a slide movable toward and away from said tool, a support for a folded sweat-band comprising an arm projecting outwardly from said slide adapted to enter the loop of said folded sweat-band and adapted to position said sweat-band with the end portions thereof in operative relation to said tool, indexing means graduated in head sizes adapted to indicate the position of said slide with respect to said tool, and means for moving said slide adapted when actuated to move said slide through a distance equal to the distance between two adjacent graduations of said indexing means.
7. In apparatus of the class described, in combination, a cutting tool, a slide movable toward and away from said tool, a support for a folded sweat-band comprising an arm projecting outwardly from said slide adapted to enter the loop of said folded sweat-band and adapted to position said sweat-band with the end portions thereof in operative relation to said tool, means for moving said slide toward and away from said tool, and means for adjusting the angular position of said arm with respect to said tool.
8. In apparatus of the class described, in combination, a cutting tool, a slide movable toward and away from said tool, a support for a folded sweat-band comprising an arm projecting outwardly from said slide adapted to enter the loop of said folded sweat-band and adapted to position said sweat-band with the end portions thereof in operative relation to said tool, indexing means graduated in head sizes for determining the positions of said slide with respect to said tool, and means comprising a pawl and ratchet mechanism for moving said slide.
9. In apparatus of the class described, in combination, a cutting tool, a slide movable toward and away from said tool, a support for a folded sweat-band comprising an arm projecting outwardly from said slide adapted to enter the loop of said folded sweat-band and adapted to position said sweat-band with the end portions thereof in operative relation to said tool, a plurality of notches spaced longitudinally along said slide, an index finger adapted to cooperate with said notches, means for moving said slide, and means for lifting said index finger, said two means being arranged to be operated together.
10. In apparatus of the class described, in combination, a cutting tool, a slide movable toward and away from said tool, a support for a folded sweat-band comprising an arm projecting outwardly from said slide adapted to enter the loop of said folded sweat-band and adapted to position said sweat-band with the end portions thereof in operative relation to said tool, a plurality of notches spaced longitudinally along said slide, an index finger adapted to cooperate with said notches, means for lifting said index finger, and means for moving said slide adapted when operated to move said slide through a distance substantially equal to the distance between two adjacent notches.
11. In apparatus of the class described, in combination, a knife, means for supporting a sweat-band folded at its center with the juxtaposed end portions thereof in position to be cut off by said knife, said supporting means including means for coacting with the center portion of said sweat-band and predetermining the distance of said center portion from said knife, said last means being adjustable in position toward and away from said knife, a scale graduated in head sizes for indicating said adjustment, means for operating said knife to cut off the end of said sweat-band and means movable relatively to said supporting means for positively moving said supporting means toward said knife.
12. In apparatus of the class described, in combination, a knife, means for supporting a sweat-band folded at its center with the juxtaposed end portions thereof in position to be cut off by said knife, said supporting means including means for coacting with the center portion of said sweat-band and predetermining the distance of said center portion from said knife, said supporting means being slideable toward and away from said knife and adjustable angularly with respect to said knife to change the angular relation between said knife and the end portion of said sweat-band.
13. In apparatus of the class described, in combination, a knife, means for supporting a sweat-band folded at its center with the juxtaposed end portions thereof in position to be cut off by said knife, said supporting means including means for coacting with the center portion of said sweat-band and predetermining the distance of said center portion from said knife, said last means being adjustable in position toward and away from said knife, a scale graduated in head sizes for indicating said adjustment, said supporting means being adjustable angularly with respect to said knife to change the angular relation between said knife and the end portion of said sweat-band, and means for operating said knife to cut off the end of said sweat-band.
14. In apparatus of the class described, in combination, a knife, a base, a slidable support on said base for supporting a sweat-band

folded at its center with juxtaposed end portions thereof in position to be cut off by said knife, said support having means for coacting with the center portion of said sweat-band and predetermining the distance of said center portion from said knife, said support being pivotally mounted on said base for swinging movement thereon to swing said sweat-band with respect to said knife, and means for operating said knife to cut off the end of said sweat-band at an angle determined by the relative angular positions of said support and said knife.

15. In apparatus of the class described, in combination, a knife, a base, a support on said base for supporting a sweat-band folded at its center with juxtaposed end portions thereof in position to be cut off by said knife, said support having means for coacting with the center portion of said sweat-band and predetermining the distance of said center portion from said knife, said means being adjustable in position relative to said knife in a direction toward and away therefrom to change the length to which the knife will cut the sweat-band, and a scale graduated in head sizes for indicating said adjustment, said support being pivotally mounted on said base for swinging movement thereon to swing said sweat-band with respect to said knife, and means for operating said knife to cut off the end of said sweat-band at an angle determined by the relative angular positions of said support and said knife.

35. 16. The herein described art of fitting sweat-bands to hats which consists in folding the unfinished sweat-band substantially midway between its ends, rigidly supporting said band at said fold, juxtaposing the portions on the two sides of said fold face to face substantially one over the other, bringing the registering end portions under a knife positioned transversely thereof at a predetermined distance from said fold and at a predetermined angle thereto, operating said knife simultaneously to cut off said end portions, and joining the cut ends of said band in abutting relation to provide a finished sweat-band of predetermined hat size having 50 a greater diameter at the bottom than at the top.

In testimony whereof, I have signed my name to this specification this twenty-third day of December, 1926.

85 RALPH K. REYNOLDS.
